METHOD OF RIFLING GUN BARRELS

Oliver W. Bonnaffon, Hudson, Mass., assignor to
The Lapointe Machine Tool Company, Hudson,
Mass., a corporation of Maine

Application May 22, 1941, Serial No. 394,693

3 Claims. (Cl. 90—28.1)

This invention relates to finishing the barrels of rifles or other types of guns in which shallow and slightly helical rifle grooves are provided to give the projectile a spinning or twisting motion as it leaves the gun.

It is the general object of my present invention to provide an improved method of broaching such helical grooves in a gun barrel, and also to provide an improved and accurate method of reaming the gun barrel after the grooves are broached.

My invention further relates to certain ordered procedure which will be hereinafter described and more particularly pointed out in the appended claims.

Certain tools adapted for use in the practice of my improved method are shown in the drawings, in which

Fig. 1 is a partial side elevation of a broach adapted for performing the first grooving operation by my improved method;

Figs. 2, 3, 4, and 5 are sectional end elevations, taken along the lines 2—2, 3—3, 4—4 and 5—5 respectively in Fig. 1;

Fig. 6 is a partial side elevation of a broach adapted for performing the second grooving operation;

Figs. 7, 8, 9 and 10 are sectional end elevations, taken along the lines 7—7, 8—8, 9—9 and 10—10 in Fig. 6 respectively;

Fig. 11 is a partial side elevation of a broach adapted for performing the third grooving operation;

Figs. 12, 13, 14 and 15 are sectional end elevations, taken along the lines 12—12, 13—13, 14—14 and 15—15 in Fig. 11 respectively;

Fig. 16 is a partial side elevation of a broach adapted for performing the fourth grooving operation;

Figs. 17, 18, 19 and 20 are sectional end elevations, taken along the lines 17—17, 18—18, 19—19 and 20—20 in Fig. 16 respectively;

Fig. 21 is a partial side elevation of a broach adapted for performing the final or reaming operation by my improved method;

Figs. 22, 23, 24 and 25 are sectional end elevations, taken along the lines 22—22, 23—23, 24—24 and 25—25 in Fig. 21 respectively;

Fig. 26 is a transverse sectional view of a gun barrel to be rifled;

Fig. 27 is a transverse sectional view of the same barrel after it has been rifled by my improved method; and

Fig. 28 is a partial transverse sectional view showing the portions of stock removed by suc-

cessive operation of the tools shown in Figs. 1 to 25.

In order that the advantages of my improved method may be more clearly understood, it may be stated briefly that the common method of rifling a gun barrel is to cut each groove separately by repeated passes of a single-tooth cutter therethrough. As a considerable number of grooves are required, which number increases with the diameter of the bore, the rifling of a gun barrel by this heretofore common practice consumes a large amount of time and is correspondingly expensive. By my improved method, I produce a completely rifled and reamed barrel by passing a limited number of broaches once only through the barrel to be rifled. Each of these broaches operates simultaneously on all of the grooves to be formed in the barrel.

In Fig. 26 I have shown a transverse section 20 of a gun barrel B to be grooved or rifled and for purposes of illustration have indicated that the barrel has an internal diameter of .296". In Fig. 27 I have shown a transverse section of the same barrel B after the barrel has been rifled and finished internally by my improved method. The reamed internal diameter is now .301" and the barrel has been provided with four grooves G which are equally spaced and which have an outside diameter of .310" between the bottoms of 30 opposite grooves.

In Fig. 28 I have shown an enlarged transverse section in which the portions of stock removed by successive operations are indicated at a, b, c, d and e.

Briefly stated, relatively narrow grooves of partial depth are first produced by removing the portions a by the broach shown in Fig. 1, with either the broach or the work positively rotated to provide the correct twist or pitch. The grooves 40 are then broached to substantially full depth but with each groove slightly reduced in width by removal of the portion indicated at b in Fig. 28 and by operation of the tool shown in Fig. 6.

The third tool shown in Fig. 11 then removes 45 spaced portions c, thus widening the groove to substantially full depth. Each groove is then completed by the tool shown in Fig. 16, which removes spaced portions d to provide full width of groove and also takes a slight finish cut over the entire bottom of the groove.

The bore is then reamed by the tool shown in Fig. 21, which is provided with ribs which center and guide the tool in the finished rifle grooves and with round cutters which ream the bore of 55 the barrel by removing the thin layer of stock

indicated at *e* in Fig. 28. During this reaming operation, the broach has a relative twisting or helical motion in the bore, so that any tool marks produced in reaming will be parallel to the rifle grooves, rather than parallel to the longitudinal axis of the barrel.

The specific construction of the reaming broach per se, shown in Fig. 21, and the advantages thereof are fully described in the prior application of Willrose J. Phaneuf, Serial No. 380,055 and 10 are not specifically claimed herein.

Positive rotation of the tool or the work is necessary only during the initial broaching operation.

I will now describe in more detail the specific 15 construction of each of the five broaches shown in detail in Figs. 1 to 25 inclusive.

In Figs. 1 to 5, I have shown the construction of the first broach, which is provided with a leading pilot section 40, a first cutter 41, a plurality of intermediate cutters not shown, a last cutter 42, and a following pilot section 43. The leading pilot section 40 is of circular cross section, as shown in Fig. 2, and is slidable with slight clearance in the bore of the gun barrel which is to be rifled. Assuming the bore to be .296", as indicated in Fig. 26, the pilot 40 may have a diameter of .295".

The first cutter 41 is shown as having four 20 equally spaced grooving projections. Each projection has a width of .100", and the outside diameter of the projections is .297". Any desired number of intermediate cutters may be interposed between the first cutter 41 and the last cutter 42, which is shown as having an outside diameter of .303".

The following pilot 43 is similar in section to the cutters but without cutting edges. The spiral ribs on the pilot are also of slightly less width and of slightly less outside diameter, as indicated in Fig. 5.

During the operation of the broach shown in Figs. 1 to 5, it will be understood, as previously stated, that either the broach or the work will be positively rotated to produce the desired twist or pitch for the rifle grooves, which pitch must of course correspond to the pitch of the teeth on the cutters and to the pitch of the ribs on the following pilot section 43. All of the broaches except the first are provided with spirally ribbed leading pilots and these broaches will follow the pitch established in the first operation without positive rotation of either broach or work.

The broach for the second operation is shown in Figs. 6 to 10, said broach comprising a leading pilot portion 50, a first cutter 51, intermediate cutters not shown, a last cutter 52, and a following pilot 53. The leading pilot 50 corresponds in construction and dimensions to the following pilot 43 of the first broach.

It will be noted that the width of the projections on the cutters 51 to 52 is slightly reduced to .095" while the outside diameter is gradually increased to .309". The ribs of the following pilot portion 53 are slightly reduced in width to .090" and the outside diameter to .308" for clearance.

The third broach, shown in Figs. 11 to 15 respectively, comprises a leading pilot portion 60 with a first cutter 61, intermediate cutters not shown, a final cutter 62, and a following pilot 63, the construction being identical with that shown in Fig. 6 except for variations in dimensions as shown in Figs. 12 to 15. The projections in the cutters 61 to 62 are increased to .150" in width 75

and to an outside diameter in the last cutter 62 of .309".

The fourth cutter, shown in Figs. 16 to 20, is similar to the second and third cutters and comprises a leading pilot portion 70, first cutter 71, intermediate cutters not shown, last cutter 72 and following pilot 73. The cutter projections on the fourth broach are increased to a final width of .175" and are gradually increased to a final outside diameter in the last cutter 72 of .310".

The final broach shown in Figs. 21 to 25 has a leading pilot portion 80, a first cutter 81, a middle pilot portion 82, a last cutter 83, and a following pilot portion 84, together with intermediate cutters not shown. This final broach is used for reaming the bore of the barrel. The broach is centered by the ribs on the pilots, which have an outside diameter of .309", so that they are a close sliding fit in the broached grooves which have an outside diameter of .310". All of the cutters in this fifth broach are of circular cross section and ream the bore of the barrel to a final and desired diameter of .301".

As previously explained, the reaming broach shown in Fig. 21 is guided in a helical path corresponding to the pitch of the rifle grooves, so that any tool marks produced by the cutters 81 to 83 are parallel to the rifle grooves and thus do not retard the flight of the projectile, as might be the case if the tool marks were parallel to the longitudinal axis and at an angle to the rifle grooves.

Reference to Fig. 28 will indicate that the portions of stock to be removed by the different broaches are carefully distributed and approximately equal in cross sectional area, so that each broach performs substantially the same amount of work and may be operated at the same speed.

By the use of a set of broaches as herein described, and by following the procedure outlined, a gun barrel can be provided with a set of rifle grooves in much less time than has been previously necessary and with superior accuracy.

It will be understood that the dimensions shown in the drawings are illustrative only and may be varied to suit the size and material of the barrels to be rifled. It will also be understood that the number of successive tools used in the production of finished rifle grooves may be increased or decreased also in accordance with the size or the material of the barrels. The number of grooves may also be varied.

For convenience, the significant dimensions of the operative portions of the tools shown in the drawings are assembled in the following table but, as previously stated, these dimensions are illustrative only.

	First pilot		First cutter		Last cutter		Last pilot	
	OD	Width	OD	Width	OD	Width	OD	Width
1st tool.....	.295	Rd	.297	.100	.303	.100	.302	.095
2nd tool.....	.302	.095	.3035	.095	.309	.095	.308	.090
3rd tool.....	.308	.090	.298	.150	.309	.090	.308	.145
4th tool.....	.308	.145	.298	.175	.310	.175	.309	.160
5th tool.....	.309	.160	.297	Rd	.301	Rd	.309	.160

Having thus described my invention and the advantages thereof, I do not wish to be limited to the details herein disclosed, otherwise than as set forth in the claims, but what I claim is:

1. The method of rifling gun barrels which comprises simultaneously producing a plurality of finished helical rifle grooves in said barrel by successively removing approximately equal incre-

ments of material from all of said grooves by a series of broaching operations, and thereafter finishing the bore of said gun by passing an annular broach therethrough which is relatively guided in a helical path concentric with said rifle grooves and of the same twist as said grooves.

2. The method of rifling gun barrels which comprises simultaneously broaching a plurality of initial helical grooves in a gun barrel, increasing both the depth and the width of said grooves by successive broaching operations, each performed on all of said grooves simultaneously, and thereafter finishing the bore of said gun by passing an annular broach therethrough which is relatively guided in a helical path concentric with

10 said rifle grooves and of the same twist as said grooves.

3. The method of rifling gun barrels which comprises simultaneously broaching a plurality of initial helical grooves in a gun barrel, increasing both the depth and the width of said grooves by successive broaching operations, each performed on all of said grooves simultaneously and each removing approximately equal increments of material from said grooves, and thereafter finishing the bore of said gun by passing an annular broach therethrough which is guided in a helical path by and concentric with said rifle grooves.

OLIVER W. BONNAFE.
